UNITED STATES PATENT OFFICE

105,850

DESIGN FOR A GAME BOARD

David J. Edwards, Hollywood, Calif.

Application May 4, 1937, Serial No. 69,148

Term of patent 3½ years

To all whom it may concern:

Be it known that I, David J. Edwards, a citizen of the United States, residing at Hollywood, in the county of Los Angeles and State of California, have invented a new, original, and ornamental Design for a Game Board, of which the following is a specification, reference being had to the accompanying drawing, forming part thereof.

The figure is a top plan view of a game board showing my design.

The article is the conventional type of game board base and is of no appreciable thickness.

I claim:

The ornamental design for a game board as shown and described.

DAVID J. EDWARDS.
